UNITED STATES PATENT OFFICE.

MILLIE E. RYAN, OF CHICAGO, ILLINOIS.

WINDOW-CLEANER.

1,315,161.

Specification of Letters Patent.

Patented Sept. 2, 1919.

Application filed September 9, 1918. Serial No. 253,169.

To all whom it may concern:

Be it known that I, MILLIE E. RYAN, a citizen of the United States, and a resident of Chicago, in the county of Cook and State 5 of Illinois, have invented certain new and useful Improvements in Window-Cleaners, of which the following is a specification.

This invention relates to improvements 10 in devices to be used for cleaning the glass panes of windows, and it consists in certain peculiarities of the construction, novel arrangement and operation of the various parts thereof, as will be hereinafter more fully set forth and specifically claimed.

15 The principal object of the invention is to provide a cleaner for windows, which shall be simple and inexpensive in construction, strong, durable and efficient in operation, and so made as to be particularly adapted 20 for cleaning the panes of both the upper and lower sashes of windows without the necessity of the operator getting outside of the window-frame. Another object of the invention is to provide a cleaner or polisher 25 for windows or other flat surfaces, such as the walls and ceilings of rooms, the tops of tables and the walls of furniture, which can be operated manually, or when necessary, by means of a detachable handle. Still another 30 object of the invention is to provide simple and efficient means for readily securing over the rubbing face of the body of the cleaner a piece of cloth or similar material in such a manner that it can be easily detached therefrom for the purpose of being 35 washed or renewed. A still further and important object is to furnish a cleaner of such compactness or dimensions, especially in thickness, as to permit of its insertion 40 and effective operation between and on the adjacent surfaces of the window panes when they are placed in parallelism by raising the lower sash or lowering the upper one in the operation of cleaning the windows.

45 Other objects and advantages of the invention will be disclosed in the subjoined description and explanation.

In the accompanying drawing which serves to illustrate an embodiment of the 50 invention,

Figure 1 is a face view of the rear surface of the cleaner showing a portion of the cleaning cloth or material removed and illustrating a portion only of the handle 55 of the device.

Fig. 2 is a cross sectional view taken on

line 2—2 of Fig. 1 looking in the direction indicated by the arrows, and

Fig. 3 is a detached perspective view of a portion of the handle showing a modification in the means of securing it to the holder or holding plate therefor, and also illustrating a modification in the construction of said holder or plate.

Like numerals of reference refer to the 65 corresponding parts throughout the different views of the drawing.

The reference numeral 5 designates the body of the cleaner, which body may be made of any suitable size, form and material, but preferably substantially rectangular in shape as shown, and of metal. The body plate 5 is by preference formed in its perimeter or edges with a groove 6 for the reception of a wire 7 which is extended entirely around the plate or body 5 and is securely held in place thereon by means of the groove 6 in which it is located, and by having its ends united or twisted together as shown at 8, Fig. 1 of the drawing. In said view it will be observed that the body or plate 5 is provided at each of its corners with a cut out portion 9 and intermediate of its corners with similar cut out portions. At each of said cut out portions the border wire 7 is formed into an inwardly extended loop each of which has its inner end pointed as shown. Each of said loops is bent outwardly from the plate or body 5 near the juncture of the loop with the wire 7 and then toward said body with its free end turned outwardly therefrom, thus forming spring piercing hooks or loops 10 for holding the cleaning or polishing cloth or material 11 in its operative position 95 on the body 5 of the cleaner. The rear surface of the body or plate 5, or that surface opposite the surface adjacent to the window pane or other surface to be cleaned, is provided with a number of projections 12 and 13, the projections 12 being located in a parallel line with each other on one side of the longitudinal axis of the body 5 and the projections 13 being located on a parallel line on the other side of said axis. 100 About midway between one of the projections 12 and one of the projections 13 the body or plate 5 is provided on its rear surface with another projection 14 which is substantially semi-circular in shape and has its straight edge presented toward the center of the body 5 as is clearly shown in

Fig. 1 of the drawing. Pivots mounted on the projection 14 is a button or catch 15 which is used to hold one end of the handle plate 16 or holder for the handle in position 5 on the body of the cleaner near the projections 12 and 13 opposite the projection 14, the body or plate 5 is provided with a pair of openings 17, which, as shown are spaced apart and are located between the 10 parallel lines on which the projections 12 and 13 are arranged. The openings 17 are inclined from the rear surface of the body 5 toward its end adjacent thereto and are for the reception of a pair of arms or projections 18 with which one end of the plate or handle holder 16 is provided. The arms 18 are curved or inclined from the plate 16 to correspond with the inclination of the 15 openings 17 in which they fit so as to hold 20 the end of the plate 16 opposite the projection 14 securely and in close contact with the rear surface of the body 5 of the cleaner. The plate 16 is provided at one 25 of its side edges with a pair of spaced apart projections 19 each of which is transversely apertured to receive a pintle 20 which is passed through a suitable opening in the projection 21 of the handle 22 so as to 30 pivotally secure the handle to the plate 16 or holder therefor.

By the foregoing arrangement and construction it is apparent that the projections 18 on the plate 16 can be placed in the openings 17 and the said plate can then be placed between the projections 12 and 13 and firmly locked in position by means of the catch 15 on the projection 14 which latter projection with the projections 18 and 35 openings 17 will prevent longitudinal movement of the plate 16 or handle holder while the projections 12 and 13 will prevent lateral movement thereof.

When the parts of the device are made of metal the projections 12, 13 and 14 may 40 be made integral with the body 5 by a stamping process, and it is obvious that the projections 19 on the plate 16 as well as the projection 21 on the handle 22 can be made integrally with said parts. It is further 45 apparent that the projections 19 and the projection 21 when so made will lie in substantially the same plane with the plate 16 thus offering no additional thickness to said plate or holder.

In Fig. 3 of the drawing I have shown a 50 modification in the construction of the plate holder and in the manner of securing the handle 22 thereto which consists in employing a hinge 23 for pivotally uniting the handle to the plate 16 which hinge is countersunk in both the plate and the handle so as 55 to reduce to a minimum the thickness of said parts. In this modification which is particularly intended when the parts are made 60 of wood a pair of projections or arm 18^a are

fastened to the rear surface of the plate 16 near one of its ends by means of screws instead of being made integrally with said plate as in the other construction. The projections 18^a are of substantially the same 70 shape or inclination as the projections 18 in the first above described construction and are used for engaging the openings 17 in the body 5 of the cleaner. It will be noticed that the body 5 is provided with a transverse recess 24 which is employed to receive a strap 25 of strong cloth or leather, which strap is secured at its ends to the body 5 near its side edges, and is designed as a holder for the device when it is desired to manually 75 operate it, or to dispense with the handle and its plate. It is obvious that by placing the hand between the strap 25 and the body 5 the device can be readily manipulated for 80 cleaning or polishing furniture and the like. 85

The cloth or cleaning material should be of such size as to cover the entire front face of the body and permit its edges to overlap the edges of the body on its rear surface and to be engaged or held by the spring 90 piercing loops 10 of the border wire, which loops can be readily forced through the cloth near its edges as is obvious. The cloth or cleaning material will, of course, possess considerable elasticity, thus enabling it to 95 be stretched over the front face of the body when the piercing loops are being forced through the same near its edges. After this has been done, that portion of the cleaning material located on the front face of the 100 body will contract or shrink, thus preventing undue wrinkling or sagging thereof.

By providing the body 5 with the cut away portions 9 and locating said cut away parts in spaced relation, and by placing the serpentine shaped spring loops 10 so as to extend inwardly of the cut away portions it is manifest that the cleaning cloth or material 11 will be securely held by said springs and cut away portions against movement on the body in the operation of the 110 cleaner.

Instead of providing the rear surface of the body 5 with the transverse depression or recess 24 for the reception of the strap 25, 115 the same may be omitted and the handle plate 16 may be provided with a transverse recess 26 on its surface adjacent to the body 5 for the reception of said strap.

Having thus fully described my invention, what I claim as new and desire to secure by Letters Patent is—

1. In a window cleaner, the combination with a flat faced body, of a handle secured thereto, a wire located on the border of the 125 body and having spaced apart inwardly extended loops, and a cleaning cloth covering the front face of the body and overlapping the edges thereof and engaged by said loops.
2. In a window cleaner, the combination 130

with a flat faced body having a groove in its periphery and provided in its edges with spaced apart cut-away portions, of a handle secured to the rear face of the body 5 at about its middle, a wire located in said groove on the border of the body and having spaced apart and inwardly extended piercing and clamping loops located at said cut-

away portions, and a cleaning cloth covering the front face of the body and overlapping the edges thereof and pierced and clamped by said loops. 10

MILLIE E. RYAN.
